UNITED STATES PATENT OFFICE.

HOLGER W. ARONSON, OF ST. PAUL, MINNESOTA, ASSIGNOR OF ONE-HALF TO EDWARD SWANSON AND ONE-HALF TO ALBIN R. SWANSON, BOTH OF ST. PAUL, MINNESOTA.

BRUSH-TUFTING MACHINE.

Refiled for abandoned application Serial No. 344,733, filed December 13, 1919. This application filed October 15, 1923. Serial No. 668,757.

To all whom it may concern:

Be it known that I, HOLGER W. ARONSON, a citizen of the United States, residing at St. Paul, in the county of Ramsey and State 5 of Minnesota, have invented a new and useful Improvement in Brush-Tufting Machines, of which the following is a specification.

This application is a substitute for my 10 abandoned application filed Dec. 13, 1919, Serial No. 344,733.

My invention relates to a brush tufting machine which is designed to draw the tufts which make up a brush into the brush head 15 in an easy and effecting manner. The operating parts of my device are of extremely simple construction so that it does not require one very skilled in the brush making art to learn to operate my device or to become thoroughly familiar with the operation 20 so as to readily operate the machine to rapidly fill a brush head with bristle tufts.

An essential feature in making a good brush, which is composed of a series of bristle tufts held in the brush head by wire loops, is to have each tuft large enough to fit the tuft socket in the brush head tightly and if the brush is made up in this manner the life of the same is greatly increased. 25 Therefore, it is very important in the making of a good bristle brush to have each tuft of a certain size and to draw the same tightly into the brush head without breaking the wire loop which holds the tuft. My device 30 is arranged so that the operator can manipulate the same very rapidly and thus enable him to fill a large number of brush heads in a comparatively short time. An essential feature of my device is the conveniently arranging of the various parts 35 for the operator.

It has been found not to be practical to draw the wire loops which hold the bristle tufts into the brush head too tight, such as 40 has been done with mechanically operated devices, as otherwise they are liable to break and this is detrimental in the filling of a brush head, because if the wire breaks it takes time to repair the same before the 45 operator can again continue to draw more

bristle tufts into the brush head. Therefore, an essential feature of my device is in means which are arranged so that the operator can manually operate the wire drawing mechanism to pull the tufts into the brush head and he can readily tell how much force is necessary for the same. It is also desirable to operate at times the wire spool in either direction and my device is designed to readily operate in either direction. 55

In the drawings forming part of this specification:

Figure 1 is a front view of my brush tuft drawing machine.

Figure 2 is an end view of Figure 1, a 60 portion of which is broken away.

Figure 3 is a section on the line 3—3 of Figure 2.

Figure 4 is a section on the line 4—4 of Figure 3. 70

Figure 5 is a front view of a different construction of my device.

Figure 6 is an end view of the device illustrated in Figure 5, a portion of which is broken away. 75

Figure 7 is a view of a tool which is used in connection with my device.

The drawings illustrate the brush drawing machine A provided with a brush head clamp B into which the brush head C can be 80 readily clamped or disengaged so as to insert another brush head. The clamp B is secured to a suitable bench or table 10, being positioned in a forwardly extending angle by the block 11 to which the brackets 85 12 of the clamp B are rigidly secured. A longitudinally extending clamping bar 13 is held in position by the coil springs 14, which are positioned between the brackets 12 and which tend to force the clamping 90 bar 13 upward so that when the cam levers 15, which are pivotally connected to the upper ends of the brackets 12, are released out of clamping position, the bar 13 is raised to allow the brush head C to be freely disengaged from the clamp B. The brush head C can be easily inserted in the clamp B owing to the springs 14 holding the clamping bar 13 out of engaging position, and by 95 operating the cam levers 15 into locking position. 100

sition, the clamping bar 13 is forced into engagement with the brush head C to rigidly clamp the brush head to hold it in position while it is being filled with bristle tufts.

5 It is very desirable to have the clamp B set at a forwardly inclined angle toward the operator so that the brush head is readily accessible to him.

Arms 16 extend forward from the bench 10 or table 10 and are adapted to support the longitudinally extending bar 17 on which the spool of wire D is held freely movable longitudinally of the bar 17 but against rotation on the bar, due to the angular shape 15 of the bar 17 and to a similar shaped opening formed in the axis of the spool D. When the shaft or bar 17 is rotated by the handle 18, the spool D can be moved longitudinally of the bar 17 to position the spool, with its 20 wire 19, directly in line with the bristle tuft opening in which the operator is about to draw a bristle tuft so that when the wire 19 is forced into one of the tuft openings 20 formed in the brush head C, by using 25 the tool E the wire is extended through the tuft opening 20 to form a receiving loop 21 into which a bristle tuft F is inserted and by engaging the handle 18, the operator rotates the spool D to draw the wire 19 sufficiently 30 tight to pull the tuft F into the enlarged portion 22 of the opening 20 to firmly hold the tuft in the brush head C.

The free longitudinal movement of the spool D on the shaft 17 allows the spool to 35 be so positioned that the wire 19 will extend directly in line with the opening in which the operator is pulling or desires to insert a bristle tuft in the head C, so as to give a straight pull on the wire 19 and thereby prevent kinking of the wire and transmitting the tension on the wire directly to the hand 40 of the operator engaging the handle 18. This construction prevents the operator from readily breaking the wire 19 and also overcomes any unnecessary friction on the wire.

An arm 23 is pivotally connected to the shaft 24 so as to be freely moved longitudinally on the shaft and is formed with a forward engaging end 25 which engages against the wire 19 on the spool D to hold the same against unwinding during the operation of the device A. The rear end of the arm 23 is formed with a weighted portion 26, which is 50 of suitable size to hold the forward end 25 against the wire on the spool with sufficient friction to keep the wire taut on the spool and to prevent the spool from readily turning. In this manner, the arm 23 forms a 55 check against the free rotation of the spool D, which firmly holds the wire 19 on the spool.

In operating the device A, it is very often 60 desirable to rotate the handle 18 in a backward direction to unwind the wire 19 on the

spool D, for instance, when it is desired to insert a portion of the wire through one of the openings 20 in the brush head, the operator can quickly rotate the spool D in either direction so that the device can be operated 70 very rapidly after the operator has become familiar with the same with practically little or no danger of breaking the wire 19 and yet insuring that the tufts F are of sufficient size to make up a good substantial brush. 75 It requires considerable force to pull one of the tufts F into place but by means of the operating handle 18, which can be of suitable proportions, the proper leverage is secured to readily accomplish this purpose and 80 the fact that the tension on the wire 19 is directly transmitted to the operator's hand is an important feature of the invention.

The construction illustrated in Figures 5 and 6 is identical in the clamping means of the device A, and wire holding mechanism. The spool holding shaft 17 in this construction is connected by a suitable chain 27 and sprockets 28 and 29 to the foot operating mechanism 30, the crank arm of which is 90 held in suitable bearings in an ordinary, well known manner. By means of this construction, the operator of the device A can use his feet to rotate the spool D in either direction to either draw the wire 19 so as to pull a tuft F into the brush head C or to give the desired slack to the same by rotating in the opposite direction. This construction allows the operator to have both hands free 95 at all times for use in operating the device and thereby allows him to manipulate the same rapidly, filling a large number of brush heads C in a very short time. The wire 19 is threaded from one opening 20 to another in the brush head until the entire 105 brush head is filled with bristle tufts F to make up a brush of the desired construction, and it is most desirable to have the wire 19 continuous and not broken so as to hold the bristle tufts F tightly in the brush head. 110 By means of my device a larger bristle tuft F can be more easily drawn into the brush head and thus give a very durable brush. Heretofore many brushes have been made with tufts too small for the tuft openings in 115 the brush heads and thus it was only a short time before the bristles came out of the brushes and they would be worn out. The ease with which the operator draws the proper sized tufts into the brush head with 120 my device makes it more easy to manufacture better brushes.

In accordance with the patent statutes, I have described the principles of operation of my invention, together with the apparatus which I now consider to represent the best embodiment thereof, but I desire to have it understood that the construction shown is only illustrative and that the invention can be carried out by other means 130

and applied to uses other than those above set forth within the scope of the following claims.

I claim:

- 5 1. A brush tufting machine comprising clamping jaws adapted to hold a brush head rigidly, cam levers for setting said jaws, resilient means for spreading said jaws from the brush head, a spool shaft extending below said clamp adapted to carry a spool of wire freely movable longitudinally of said shaft and means for operating said shaft for the purposes specified. 50
- 10 2. A brush tufting device comprising a brush head clamp, a longitudinal shaft, supports for said shaft, a spool of wire slidably mounted on said shaft, said shaft being formed to prevent rotation of the spool thereon and means for rotating said shaft 55 and spool to draw the loop formed in said wire into the brush head held in said clamp to tightly pull the tuft or bristles into the said brush head. 60
- 15 3. A brush tufting device, including means for rigidly holding a brush head, means for supporting a spool of wire so that it is longitudinally movable on said supporting means adjacent said brush holding means to extend the wire on said spool in line with the openings formed in the brush head held by said means and means for rotating said spool in either direction for the purposes specified. 65
- 20 4. A brush tufting device, a frame brush head clamping jaws supported at an angle to said frame to extend toward the operator, resilient means for spreading the same, means for supporting a spool of wire so that it is longitudinally slidably on said supporting means along the side of said jaws and means for rotating said spool in either direction. 70
- 25 5. A brush tufting machine, including an inclined adjustable clamp for rigidly holding a brush head, means for rotatably holding a spool of wire so that said spool is freely movable longitudinally of said clamp 75
- means for retarding free rotation of said spool and foot means adapted to operate the spool to rotate the same in either direction for the purposes specified. 80
6. A brush tufting apparatus, including adjustable clamping jaws for rigidly holding a brush head, resilient means for spreading said jaws from the brush head, cam levers for setting said jaws in locking position, means for holding said jaws to project the upper portion of the same toward the operator, a shaft extending longitudinally of said jaws, a wire holding spool keyed to said shaft and freely movable longitudinally thereon but held against rotary motion thereon, wire engaging means adapted to frictionally engage and check the unwinding of the wire on said spool, said engaging means being movable with said spool longitudinally of said jaws and means for operating said shaft to rotate said spool in either direction. 85
7. A brush tufting machine, including clamping means for holding a brush head, a wire holding spool, means for supporting said spool so that it is longitudinally movable on said supporting means, wire engaging means for frictionally engaging the wire on said spool movable longitudinally with said spool and means for rotating said spool and holding means to draw bristle tufts into a brush head held in said clamp. 90
8. A brush tufting machine, including a clamping device adapted to rigidly hold a brush head, a wire holding spool, means for holding said clamping device inclined toward said spool, means for supporting said spool so that it is movable longitudinally of said clamping device and a pivoted arm adapted to frictionally engage the wire on said spool and movable simultaneously with said spool in a longitudinal direction in relation to said clamping device for the purposes specified. 95
